Inventor

William F. McDADE.

UNITED STATES PATENT OFFICE.

WILLIAM F. McDADE, OF WILMINGTON, DELAWARE.

STEEL RAIL.

1,236,192.

Specification of Letters Patent. Patented Aug. 7, 1917.

Application filed December 11, 1916. Serial No. 136,360.

To all whom it may concern:

Be it known that I, WILLIAM F. McDADE, a citizen of the United States, residing at the city of Wilmington, in the county of New Castle and State of Delaware, have invented certain new and useful Improvements in Steel Rails, of which the following is a specification.

My invention relates to certain improvements in the constructive arrangement of a two section steel rail spliced and bolted together and having a broad smooth tread surface as well as substantial base surface for being supported on a suitable concrete or other foundation, and the said rail sections in overlapping relationships lockingly wedged and engaged with each other.

The principal objects of my invention are first, to provide a steel-rail constructed in two wedging and engaging and overlapping sections one with the other by one section having a tread and tongue and the other having a groove between side webs; the said sections fitting each other so as to become lockingly wedged or engaged in overlapping relationship, to thereby constitute practically one continuous firmly held rail throughout to receive the dead weight or strain brought to bear thereon; and second, to provide a rail which in case of shearing or parting of the overhanging part of the tread arising from any cause, maintains a body surface sufficient for a tread by reason of the webs in the lower grooved section engaging the tongue of the upper section and the webs of the lower section entering into bearing contact with the recesses of the upper section, the groove of the lower section being narrower at the upper open end than at the base of said section.

The nature, scope and characteristic features of my present invention will be more fully understood from the following description taken in connection with the accompanying drawings forming part hereof, in which—

Figure 1, is a perspective of the two sections of the rail structurally embodying the features of my invention, and showing in dotted outline, the manner of splicing or uniting a complemental upper section of the rail to a lower section thereof.

Fig. 2, is a vertical sectional view through the rail on the line 2, 2, of Fig. 1.

Fig. 3, is a perspective view of the struc-

tural formation of the upper section of the rail.

Fig. 4, is a vertical section therethrough on the line 3, 3, of Fig. 3.

Fig. 5, is a perspective view of the structural formation of the lower section.

Fig. 6, is a vertical sectional view on the line 4, 4, of Fig. 5.

Fig. 7, is a perspective of the two sections of the rail spliced or united to each other, in overlapping relationship.

Fig. 8, is a plan view of a portion of two lower sections spliced together on the lines 6, 6 and 9, 9, of Fig. 7; and

Fig. 9, is a perspective view of a portion of a lower section, showing the recessed or offset base of such rail section.

Referring to the drawings. A, is the lower grooved section of the rail with its side webs 8, 8, mounted on a suitable tie 15, Figs. 7 and 8. B, is the upper section with its depending tongue 18. The groove 23, between the webs 8, 8, is narrower in the upper portion than at the base 19, as will be presently fully explained. The under side of the head 75 of the upper section B, of the rail is formed with longitudinal recesses 7, 7, for the upper edges of the side webs 8, 8 to engage, as clearly shown in Fig. 2, and with the tongue 18, of the upper section in bearing contact 80 with the base of the lower section. The narrowing of the groove 23, lockingly wedges or holds the said tongue 18, securely in position, without regard to what shearing or other mishaps may occur to the overhanging 90 portion of the tread portion of the upper section B. The two sections united to each other overlap in a longitudinal direction, as clearly shown in Figs. 1 and 7. The tongue of the section B, is offset at both ends, re- 95

spectively, as indicated at 25 and 26, in order that complemental upper sections may be spliced or united therewith, for example, in the manner as clearly shown in Figs. 1, 7 and 8. In the portions 30, 31, where offset, 100 as in Fig. 3, the upper section B, is provided with openings 10 and 11 and in between with openings 16, and also the webs of the lower section A, are provided with openings 16, 16 and 11 respectively as shown in Fig. 105 5, so that when said sections are assembled or joined together the respective openings will register with each other in both the tongue 18, and the webs 8, 8, to permit of bolts, not shown, being inserted therethrough 110

for tying solidly the rail sections to other rail sections against sidewise or other movement and thus to provide a substantial, practically continuous rail. In Fig. 9, the lower section A, is shown as offset at 27, 27, to allow a certain portion of the said section in position to rest on the tie 15, as shown at 29, 29, in Fig. 8, to give each end substantially an equal bearing surface on the said tie 15; and moreover to afford the tongue 18, of the section B, an equal bearing on the bottom of the groove of the said lower section A.

Having thus described the nature and objects of my invention, what I claim as new and desire to secure by Letters Patent is:—

A rail, comprising two sections, one sec-

tion having a tongue with right-angular offsets at the respective extremities in reverse form in respect to each other and the other section provided with two vertical webs with the space formed by said webs from the base of said section contracted vertically so as to wedgingly engage the tongue-section with said web-section and the upper extremities of the said web-section fitting firmly into longitudinal recesses arranged in the underside of the head of said tongue-section and means adapted to be inserted through the webs and tongue of the respective sections in position to lock the same to each other, substantially as described.

WILLIAM F. McDADE.
